UNITED STATES PATENT OFFICE.

SIDNEY A. REEVE, OF NEW YORK, N.Y.

CAR HEATING SYSTEM

Application filed November 6, 1920. Serial No. 422,166.

To all whom it may concern:

Be it known that I, SIDNEY A. REEVE, a citizen of the United States, residing at New York city, in the county of New York and State of New York, have invented certain new and useful Improvements in Car-Heating Systems, of which the following is a specification:

My invention relates to a heating system particularly designed and intended for heating railway cars.

The invention has for its object to provide a car temperature controlled heating system of the low pressure type, which will be simple in construction and operation; give a better temperature regulation; and which will possess the characteristics and advantages of the well known low pressure system, such as uniform steam distribution throughout a train; and the prevention of freezing, bursting of pipes and waste of steam.

More specifically, one of the primary objects of the invention is to provide a car heating system capable of being operated either as an atmospheric pressure or vapor system, or as a high pressure system, in which the change of operation from the lower to the higher pressure, or vice versa, is accomplished automatically preferably in accordance with the needs of the car for heat.

A further object is to so arrange the controlling devices in a system of this character that when the system is operated at atmospheric pressure the radiator temperature may be that of steam at atmospheric pressure or lower in accordance with the requirement of the car for heat.

40 A further object is to provide in a heating system in which the flow of steam to the radiator is controlled by a thermostat at the outlet of the radiator, certain novel arrangements whereby when the thermostat is contracted (or otherwise inactive as a controlling element) the valve associated therewith permits steam to pass directly to such thermostat, without first circulating through the radiator, these arrangements permitting inflow to the radiator to be shut off or checked by any suitable valve, thermostatically operated or otherwise, which need not itself be provided with the short circuiting means sometimes employed in the 55 radiator valves of vapor heating systems

for keeping the outlet thermostat warm; said arrangement also permitting the outlet thermostat to be set to expand (or otherwise function) at a lower temperature than that of the condensation point of steam, 60 whereby a saving may be effected in the steam employed for keeping the thermostat from freezing at such times as it receives no heating medium from the radiator.

The invention consists in the novel constructions, arrangements and combinations hereinafter described and claimed for carrying out the above stated objects and such other objects as will appear from the following description.

The invention is illustrated in certain preferred embodiments, in the accompanying drawings, in which:

Fig. 1 is a sectional elevation of the controlling and regulating apparatus.

Fig. 2 is a perspective view of the radiator inlet valve.

Fig. 3 is a perspective view of the lower face of the radiator outlet valve; and

Fig. 4 is a sectional elevation of a modified form of heating system having a plurality of independent temperature controlled radiators.

Like characters of reference designate like parts in the several figures of the drawings.

While heating systems for buildings and houses having automatic temperature control have been fairly successful, such systems when attempted to be applied to railway cars have met with only partial success. This has been due largely to the entirely different conditions encountered in railway car heating, such as sudden variations in exterior temperature of wide range, 90 due to a large number of well known causes and also because of the necessity of maintaining the temperature of the radiator outlet, that is, the drip pipe, above freezing. In the low pressure system this often requires the admission of steam to the car radiator when the temperature conditions in the car do not require it. In providing a heating system having automatic car temperature regulation, it becomes necessary, 105 therefore, to consider not only the car interior requirements but also the conditions on the exterior of the car.

In the drawings, 10 represents the branch pipe running from the usual steam supply 110

line under the car. It passes through the floor 11 of the car and is connected to the casing 12 through a valve 13. The casing 12 is subdivided into a chamber 14 providing 5 an entrance for the steam, a steam inlet chamber 15, a radiator inlet chamber 16, a radiator outlet chamber 17, and a chamber 18 to which the drip pipe 19 is connected.

The wall 20 between the chambers 14 and 10 15 is provided with a valve opening 21 having a valve seat 22 controlled by the valve 23. The valve 23 is actuated through the valve 24, by the thermostatic element 25 positioned in a housing 26 secured to the 15 outlet end of the drip pipe 19. The thermostatic element 25 is partially filled with a liquid which becomes volatile or expands at the temperature at which it is desired to close the valve port 21. The thermostatic 20 element and its supporting structure is of well known construction and is universally employed on railway cars and accordingly need not be further described. The valve rod 24 is provided with a plurality of 25 grooves or recesses 27 which provide a passage from the chamber 15 into the chamber 18 through the wall 28 when the thermostatic element 15 is in its position of greatest contraction. During the normal operation 30 of the valve 23, the thermostat 25 is expanded sufficiently to cut off passage from the chamber 15 to the chamber 18, through the recesses 27. As will be readily understood, the rod 24 with the recesses 27 therein and the shoulders at the lower ends of the 35 recesses constitute an auxiliary valve formed integrally with the stem of the valve 23 and adapted to be operated in unison with such valve.

40 The car radiator 29 may be of any suitable construction, having its discharge end open to the atmosphere, as hereinafter described. It may consist of the usual coil of pipe having an inlet pipe 30 and return pipe 31. The inlet pipe 30 is connected to the chamber 16, into which steam is admitted through the port 32. The port 32 is controlled by a piston valve 33 having a plurality of passages 34 through which steam may 45 pass into the chamber 16, and preferably provided with a shoulder 35 for seating at the end of its stroke. The valve closes the port when the end of the piston lies within the port 32. Preferably the valve is 50 designed to freely slide in the port, a small amount of leakage through this valve being immaterial.

55 A valve 36 controls the port 37 connecting the chambers 17 and 18. This valve is provided with notches or recesses 38 in its seat, so that the same can never be entirely closed, thus leaving the discharge end of the radiator open to the atmosphere. These recesses are of a size sufficient to permit the 60 drainage of any water of condensation

which may form in the radiator, whether the system is operating or not. The valves 33 and 36 are preferably operatively connected by a valve rod 39, which passes through the opening 40 in the wall 41. The 70 valves 33 and 36 are actuated by an arm 42 connected to a shaft 43 which passes through the side wall of the casing 12. The arm 42 is operatively connected with the valve by engagement between the valve 36 and the 75 collar 44. Connected with the shaft 43 on the exterior of the casing is another arm 45 which is actuated by the car thermostat 46 through the operating rod 47. Preferably the thermostatic element is contained within 80 a cage or housing 48 and the rod 47 is protected by a tube 48' which extends the length thereof. The thermostatic element is partially filled with a liquid adapted to 85 actuate the valves at or near the temperature at which it is desired to maintain the interior of the car. Preferably the thermostatic element is provided with adjusting means 49, by means of which the temperature at which the thermostat actuates the valve may be 90 varied. It is obvious that any other temperature controlled means may be used to actuate the radiator valve and if necessary a relay may be provided for operating the valve in connection with such thermostats 95 as are not sufficiently powerful to accomplish the operation directly. If necessary a spring 50 may be provided to aid the action of gravity in opening the valve 33 and closing the valve 36. These valves are so adjusted that the valve 36 is closed as nearly 100 as possible when there is maximum demand for steam through the inlet port 32.

Operation: Steam is admitted at the usual train line pressure to the chamber 14. Upon 105 the contraction of thermostat 25 sufficiently to open the valve 23, steam is admitted to the chamber 15 and also through the port 32 if there is any demand for steam in the radiator. When the system is cold the thermostatic element 25 contracts sufficiently to uncover the passage through the recesses 27. Water of condensation and steam then pass into the drip pipe 19 until the thermostatic element expands sufficiently to close this 110 auxiliary valve. In normal operation however, the valve 23 seldom moves far enough from its seat to bring the recesses 27 into operation, the water of condensation from the radiator serving to maintain the thermostatic element 25 at a temperature to prevent extreme contraction. Any condensate in the radiator drains through the recesses 38 in the valve 36 and into the drip pipe 19, both the radiator and the chamber 125 18 being designed to permit drainage by gravity. Preferably the thermostatic element 25 is designed to operate at a temperature lower than that usual for thermostats in the ordinary low pressure systems. This 130

temperature need only be high enough to prevent freezing.

Steam flows into the radiator 29, the condensate being forced out through the recesses 38 in the valve 36, until the thermostatic element 46 expands sufficiently to partially close the valve 33 and partially open the valve 36. In this position the system operates as the ordinary vapor system. The steam by passing out of the radiator through the port 37 and into the drip pipe 19 causes the thermostat 25 to expand and close the inlet port 21. If the car temperature rises above normal, namely above 60 or 70 degrees Fahrenheit, or at whatever temperature the thermostatic element 46 is designed to operate, the valve 33 is entirely closed. The condensation of the steam in the radiator 29 draws air through the open end of the drip pipe and the port 37 into the radiator. This air mixes with the steam in the radiator and lowers the temperature of the combined mixture of steam and air to a point considerably below 212° Fahrenheit and acts to lower the rate of heat transferred from the radiator to the car.

When the car temperature falls below normal, the thermostat 46 expands slightly and places the valves 33 and 36 in their intermediate positions and the system operates as an ordinary low pressure system. If the demand for heat becomes a maximum, the thermostat 46 contracts sufficiently to permit the valve 36 to close, leaving only the passages 33 open. The substantial closing of the port 37 to the discharge of steam raises the pressure in the radiator above atmospheric pressure and consequently raises the temperature of the radiator above 212° Fahrenheit. This increase of the radiator temperature above normal serves to increase the rate of transfer of heat to the car and causes the system to respond more quickly to the demand for heat.

The employment of high temperature steam when the demand for heat is maximum and of a low temperature mixture of air and vapor when the demand for heat is minimum, permits a better temperature regulation than could be obtained with a heating medium of substantially uniform temperature. The fact that the thermostatic element 25 acts preferably at some temperature below 212° Fahrenheit insures the presence within chamber 18 of some air mixed with the steam. When the valve 33 is closed, as the radiator condenses its contents of vapor, there is a tendency to draw steam from the chamber 15 past such valve (which tendency will be slight because there is only slight pressure difference on its two sides, as well as from the fact that it is constructed to leak as little as practicable) and also to cause a back flow of steam air mixture from chamber 18. This insures a tem-

perature within the radiator below 212° Fahrenheit whenever valve 33 may close sufficiently to call for it.

But it is to be recognized that, even if thermostat 25 operates at 212° Fahrenheit, this action will occur to some degree, because chamber 18 and the discharge end of the radiator are always open to the atmosphere. Hence, whenever valve 33 closes sufficiently to prevent a flow of steam into the radiator at a rate to compensate for the condensation some air will be drawn into and through chamber 18.

In Fig. 4 I have illustrated a modified form of heating system in which there are a plurality of radiators 51, 52 controlled independently by thermostats 53, 54. These radiators may be located in different parts or compartments of a car, and are controlled by the thermostatic conditions in the various parts of the car, at which it is desirable to locate the thermostats. As many independent radiators as necessary may be provided, each radiator being supplied with steam from a central casing 55. The central casing 55 comprises chambers 56, 57 and 58. The admission of steam from the chamber 56 to the chamber 57 is controlled by the valve 59 actuated by the thermostatic element 60 located in the mouth of the drip pipe 61. This construction is similar to that illustrated in Fig. 1 and need not be further described. From the chamber 57 supply pipes 62 lead to the various valve casings 63. The valve casings 63 are provided with radiator inlet chambers 64, vapor inlet chambers 65 and discharge chambers 66. The valves 67 and 68 are similar in construction and operation to those described in connection with Fig. 1 and control the admission of the steam to and exit from the several radiators. The operation of the thermostats 53, 54 in connection with their respective radiator valves is similar to that previously described. Return steam and water of condensation pass from the chambers 69 into the pipes 70 and thence to the drip pipe 61, these parts being arranged to permit drainage by gravity.

In general the system shown in Fig. 4 operates like that shown in Fig. 1 with the exception that the radiators are controlled independently. It will be recognized, however, that with any adjustment or position of thermostat 60 establishing a pressure within the central chamber 57 not too far above atmospheric pressure, different positions of the independent thermostats 53, 54 can and will establish different temperatures within their respective radiators. This, indeed, is especially the function of the modification shown in Fig. 4.

I claim:

1. In combination, a car heating system capable of operating at atmospheric pres-

- sure or at a higher pressure, and a thermostat to automatically effect the change from the operation at the lower pressure to that at the higher pressure, and vice versa.
5. 2. In combination, a car heating system capable of operating at atmospheric pressure or at a higher pressure, and a thermostat, subject to fluctuations in the temperature of the air in the car, to automatically effect the change from the operation at the lower pressure to that at the higher pressure, and vice versa.
10. 3. In combination, a car heating system capable of operating to produce a radiator temperature corresponding to the temperature of steam at atmospheric pressure, or radiator temperatures above or below that temperature, and a thermostat to automatically effect the change from one operation to the other.
15. 4. In combination, a car heating system capable of operating to produce a radiator temperature corresponding to the temperature of steam at atmospheric pressure, or radiator temperatures above or below that temperature, and a thermostat, subject to fluctuations in the temperature of the air in the car, to automatically effect the change from one operation to the other.
20. 5. In a car heating system, the combination with a source of supply of steam, of a radiator, a valve to control inflow to the radiator, a thermostat at the outlet of the radiator for actuating said valve, a pair of valves, one of which is open when the other is closed, and vice versa, one interposed between the aforesaid valve and radiator and the other between the radiator and said thermostat, and thermostatically actuated means for operating said pair of valves.
25. 6. In a car heating system, the combination with a source of supply of steam, of a radiator, a valve to control inflow to the radiator, a thermostat outside of the car for actuating said valve, a pair of valves, one of which is open when the other is closed, and vice versa, one interposed between the aforesaid valve and radiator and the other between the radiator and said thermostat, and thermostatically actuated
30. means for operating said pair of valves.
35. 7. In a car heating system, the combination with a source of supply of steam, of a radiator having an outlet to the atmosphere, means comprising a thermostat at said outlet for governing inflow thereto, and means actuated by fluctuations in the temperature of the car atmosphere which operates at low car temperatures for checking outflow from said radiator.
40. 8. In a car heating system, the combination with a source of supply of steam, of a radiator having an outlet to the atmosphere, and a valve to control the flow to the radiator, a thermostat at the outlet to actuate said valve, means associated with said valve whereby, when the thermostat is contracted, steam is allowed to pass directly to the thermostat without circulating through the radiator, and a second valve located between said first named valve and the radiator for checking inflow to the latter.
45. 9. In a car heating system, the combination with a source of supply of steam, of a radiator having an outlet to the atmosphere, a valve to control the flow to the radiator, a thermostat at the outlet to actuate said valve, means associated with said valve whereby, when the thermostat is contracted, steam is allowed to pass directly to the thermostat without circulating through the radiator, and a second valve located between said first named valve and the radiator for checking inflow to the latter.
50. 10. In a car heating system, the combination with a source of supply of steam, of a radiator having an outlet to the atmosphere, a valve to control the flow to the radiator, a thermostat at the outlet to actuate said valve, means associated with said valve whereby, when the thermostat is contracted, steam is allowed to pass directly to the thermostat without circulating through the radiator, and a second valve located between said first named valve and the radiator for checking inflow to the latter.
55. 11. In a car heating system, the combination with a source of supply of steam, of a radiator having an outlet to the atmosphere, a valve to control the flow to the radiator, a thermostat at the outlet to actuate said valve, means associated with said valve whereby, when the thermostat is contracted, steam is allowed to pass directly to the thermostat without circulating through the radiator, and means actuated by fluctuations in the temperature of the air in the car comprising a valve arranged between the aforesaid valve and radiator for checking inflow to the latter.
60. 12. In a car heating system, the combination with a source of supply of steam, of a radiator having an outlet to the atmosphere, a valve to control the flow to the radiator, a thermostat at the outlet to actuate said valve which functions at a temperature substantially lower than the condensation point of steam, means controlled by said thermostat and adapted, when the thermostat is contracted, to allow steam to pass directly to the thermostat without circulating through the radiator, and means located between said valve and radiator, for checking inflow to the latter.
65. 13. In a car heating system, the combination with a source of supply of steam, of a radiator having an outlet to the atmosphere, a valve to control the flow to the radiator, a thermostat at the outlet to actuate said valve which functions at a temperature sub-

stantially lower than the condensation point of steam, means associated with said valve whereby, when the thermostat is contracted, steam is allowed to pass directly to the 5 thermostat without circulating through the radiator, and means actuated by fluctuations in the temperature of the air in the car for checking inflow to the radiator.

14. In a car heating system, the combination 10 with a source of supply of steam, of a radiator having an outlet to the atmosphere, a valve to control the flow to the radiator, a thermostat at the outlet to actuate said valve, means associated with said valve 15 whereby, when the thermostat is contracted, steam is allowed to pass directly to the thermostat without circulating through the radiator, a pair of valves either one of which is open when the other is closed, one of 20 which is located between the first named valve and the radiator and the other between the radiator and thermostat, and means for operating said pair of valves.

15. In a car heating system, the combination 25 with a source of supply of steam, of a radiator having an outlet to the atmosphere, a valve to control the flow to the radiator, a thermostat at the outlet to actuate said valve, means associated with said valve 30 whereby, when the thermostat is contracted, steam is allowed to pass directly to the thermostat without circulating through the radiator, a pair of valves either one of which is open when the other is closed, one of 35 which is located between the first named valve and the radiator and the other between the radiator and the thermostat, and thermostatically actuated means for operating said pair of valves.

40 16. In a car heating system, the combination with a source of supply of steam, of a radiator having an outlet to the atmosphere, a valve to control the flow to the radiator, a thermostat at the outlet to actuate said 45 valve, means associated with said valve whereby, when the thermostat is contracted, steam is allowed to pass directly to the thermostat without circulating through the radiator, a pair of valves either one of 50 which is open when the other is closed, one of which is located between the first named valve and the radiator and the other between the radiator and thermostat, and thermostatically actuated means subject to fluctuations in the temperature of the air in the 55 car for operating said pair of valves.

17. In a car heating system, the combination 60 with a source of supply of steam, of a radiator having an outlet to the atmosphere, a valve to control the flow to the radiator, a thermostat at the outlet to actuate said valve and being arranged so as to function at a temperature substantially lower than the condensation point of steam, 65 means associated with said valve whereby,

when the thermostat is contracted, steam is allowed to pass directly to the thermostat without circulating through the radiator, a pair of valves either one of which is open when the other is closed, one of which is located between the first named valve and the radiator and the other between the radiator and thermostat, and thermostatically actuated means subject to fluctuations in the temperature of the air in the car for operating 75 said pair of valves.

18. In a car heating system, the combination 80 with a supply pipe carrying steam at a relatively high pressure, of a radiator, a valve controlled by a thermostat located outside of the car for supplying low pressure steam to said radiator, a second valve controlled by a thermostat located inside the car connected with said radiator for governing the flow of steam through said radiator 85 responsively to the temperature of the car, means for returning steam from the radiator to said first named thermostat, and means controlled by the first named thermostat for admitting steam directly from said first 90 named valve to said first named thermostat.

19. In a heating system for railway cars, the combination with a radiator in a car, and a supply pipe carrying steam at a relatively high pressure, of a valve connected with said supply pipe for supplying steam to said radiator, a thermostat without the car for controlling said valve, means associated with said valve for admitting steam directly to said thermostat when the same is below a certain temperature, valves controlled by a thermostat in the car for governing the admission of steam to said radiator and for controlling the discharge 100 of steam from said radiator, and means for conducting the steam and condensate from the radiator to said first named thermostat.

20. In a heating system for railway cars, the combination with a radiator in a car and a supply pipe carrying steam at a relatively high pressure, of a valve chamber to which said supply pipe is connected, a thermostat without the car, a valve in said chamber connected with said thermostat for controlling the admission of steam to said chamber, an auxiliary valve in said chamber and controlled by said thermostat for admitting steam from said chamber to said thermostat, connections between said chamber and said radiator for supplying steam to the radiator, a valve for controlling the supply of steam through said connections to the radiator, connections between the radiator and the thermostat for conducting the steam and condensate from the radiator to the thermostat, a valve for controlling the discharge of steam from the radiator through the connections between the radiator and the thermostat, and means actuated 115 responsively to the temperature in the car 120

- for operating the last named two valves so that one valve opens as the other valve closes.
21. In a railway car heating system, the combination with a steam supply pipe, a radiator in the car and a drip pipe extending without the car to which drip pipe the return pipe of said radiator is connected, of a chamber connecting said supply pipe and radiator, a valve for admitting steam to said chamber, a thermostat in said drip pipe connected with said valve for governing the admission of steam to said chamber responsively to the temperature in said drip pipe, an auxiliary valve controlled by said thermostat for admitting steam in limited quantities from said chamber directly to said drip pipe, to maintain the temperature in said drip pipe above freezing, a radiator valve for admitting steam from said chamber to said radiator, a return pipe valve for governing the flow from the radiator to said drip pipe, and a thermostat located within the car for governing said radiator valve responsively to the temperature of the car and for regulating the opening through said return pipe valve, said return pipe valve being provided with a permanently open port of small area. 70
22. In a railway car heating system, the combination with a steam supply pipe, a radiator in the car and a drip pipe extending without the car to which drip pipe the return pipe of said radiator is connected, of a chamber connecting said supply pipe and radiator, a valve for admitting steam at reduced pressure to said chamber, a thermostat in said drip pipe connected with said valve for governing the admission of steam to said chamber responsively to the temperature in 85 said drip pipe, an auxiliary valve controlled by said thermostat for admitting steam in limited quantities from said chamber directly to said drip pipe, to maintain the temperature in said drip pipe above freezing, a radiator valve for admitting steam from said chamber to said radiator, a thermostat located within the car for governing said radiator valve responsively to the temperature of the car and for substantially closing said return pipe valve when the temperature in the car falls below normal, so as to momentarily raise the temperature of said radiator. 90
23. In a railway car heating system, the combination with a steam supply pipe, a radiator in the car and a drip pipe extending without the car to which drip pipe the return pipe of said radiator is connected, of a chamber connecting said supply pipe and radiator, a valve for admitting steam to said chamber, a thermostat in said drip pipe connected with said valve for governing the admission of steam to said chamber responsively to the temperature in said drip pipe, an auxiliary valve controlled by said thermostat for admitting steam in limited quantities from said chamber directly to said drip pipe, to maintain the temperature in said drip pipe above freezing, a radiator valve for admitting steam from said chamber to said radiator, a thermostat located within the car for governing said radiator valve responsively to the temperature of the car and for substantially closing said return pipe valve when the temperature in the car falls below normal, so as to momentarily raise the temperature of said radiator. 100
24. In a railway car heating system, the combination with a steam supply pipe, a radiator in the car and a drip pipe extending without the car to which drip pipe the return pipe of said radiator is connected, of a chamber connecting said supply pipe and radiator, a valve for admitting steam at reduced pressure to said chamber, a thermostat in said drip pipe connected with said valve for governing the admission of steam to said chamber responsively to the temperature in 115 said drip pipe, an auxiliary valve controlled by said thermostat for admitting steam in limited quantities from said chamber directly to said drip pipe, to maintain the temperature in said drip pipe above freezing, a radiator valve for admitting steam from said chamber to said radiator, a thermostat located within the car for governing said radiator valve responsively to the temperature of the car and for substantially closing said return pipe valve when the temperature in the car falls below normal, so as to momentarily raise the temperature of said radiator. 120
25. In a railway car heating system, the combination with a steam supply pipe, a radiator in the car and a drip pipe extending without the car to which drip pipe the return pipe of said radiator is connected, of a chamber connecting said supply pipe and radiator, a valve for admitting steam at substantially atmospheric pressure to said chamber, a thermostat in said drip pipe connected with said valve for governing the admission of steam to said chamber responsively to the temperature in said drip pipe, an auxiliary valve controlled by said thermostat for admitting steam in limited quantities from said chamber directly to said drip pipe, to maintain the temperature in said drip pipe above freezing, a radiator valve for admitting steam from said chamber to said radiator, a thermostat located within the car for governing said radiator valve responsively to the temperature of the car and for substantially closing said return pipe valve when the temperature in the car falls below normal, so as to momentarily raise the temperature of said radiator. 125

to said radiator responsively to temperature demands, and means in addition to said radiator valve and also controlled by said second-named thermostat for increasing the pressure in said radiator when the car temperature falls substantially below normal.

26. In a railway car heating system, the combination with a steam supply pipe, a radiator in the car and a drip pipe extending without the car to which drip pipe the return pipe of said radiator is connected, of a chamber connecting said supply pipe and radiator, a valve for admitting steam at reduced pressure to said chamber, a thermostat in said drip pipe connected with said valve for governing the admission of steam to said chamber responsively to the temperature in said drip pipe, an auxiliary valve controlled by said thermostat for admitting steam in limited quantities from said chamber directly to said drip pipe, to maintain the temperature in said drip pipe above freezing, a radiator valve for admitting steam from said chamber to said radiator, a thermostat in said car for controlling said valve to admit steam to said radiator responsively to temperature demands, and means controlled by said second-named thermostat for admitting air into said radiator when the car temperature rises substantially above normal.

27. In a railway car heating system, the combination with a steam supply pipe, a radiator in the car and a drip pipe extending without the car to which drip pipe the return pipe of said radiator is connected, of a chamber connecting said supply pipe and radiator, a valve for admitting steam at reduced pressure to said chamber, a thermostat in said drip pipe connected with said valve for governing the admission of steam to said chamber responsively to the temperature in said drip pipe, an auxiliary valve controlled by said thermostat for admitting steam in limited quantities from said chamber directly to said drip pipe, to maintain the temperature in said drip pipe above freezing, a radiator valve for admitting steam from said chamber to said radiator, a thermostat in said car for controlling said valve to admit steam to said radiator responsively to temperature demands, and means controlled by said second-named thermostat for admitting air to the radiator when the car temperature rises sufficiently to cause the closing of said radiator valve.

28. In a railway car heating system, the combination with a steam supply pipe, a radiator in the car and a drip pipe extending without the car to which drip pipe the return pipe of said radiator is connected, of a chamber connecting said supply pipe and radiator, a valve for admitting steam to said chamber, a thermostat in said drip pipe

connected with said valve for governing the admission of steam to said chamber responsively to the temperature in said drip pipe, an auxiliary valve controlled by said thermostat for admitting steam in limited quantities from said chamber directly to said drip pipe, to maintain the temperature in said drip pipe above freezing, valves at the inlet and outlet ends of said radiator and operatively connected together so that they operate oppositely, and a thermostat located within the car for operating said valves responsively to temperature conditions in said car.

29. In a railway car heating system, the combination with a steam supply pipe, a radiator in the car, and a drip pipe extending outside of the car of an inlet chamber connecting said supply pipe with said radiator, an adjacent outlet chamber connecting the return pipe of said radiator with said drip pipe, a valve in said inlet chamber for admitting steam from said supply pipe thereto and having a controlling rod passing through the wall of said chamber into said drip pipe, a thermostat in the outlet end of said drip pipe connected to said rod and adapted to operate said valve to admit steam to said chamber responsively to the temperature in the outlet end of said drip pipe, said rod having passages cut therein adapted to connect said inlet chamber with said drip pipe for admitting steam directly thereto when said thermostat reaches its maximum contraction, valves in said inlet and outlet chambers governing the admission to and exit from said radiator, a valve rod connecting said valves, said valves being adapted to operate oppositely, and a thermostat located within the car for operating said last named valves responsively to temperature conditions in said car.

30. In a railway car heating system, the combination of a steam supply pipe, radiators in the car, a vapor regulator comprising a chamber in said car to which said supply pipe is connected, a valve in said chamber for admitting steam thereto, a drip pipe connected with said chamber and extending outside of the car, a valve rod passing through said chamber into said drip pipe, a thermostat in said drip pipe for operating said valve responsively to the temperature in said drip pipe, said valve rod having recesses therein adapted to admit steam from said chamber to said drip pipe to maintain the temperature therein above freezing, valve casings for each of said radiators comprising inlet and outlet chambers connected to the inlets and outlets, respectively, of said radiators, valves governing said inlets and outlets and having rods operatively connecting the same, said valves being adapted to operate oppo-

sitely, thermostats in said car operatively connected with said casings, respectively, for operating said valves responsively to temperature requirements, and pipes connecting said inlet chambers with said vapor regulator chamber and said outlet chambers with said drip pipe.

31. In a heating system for railway cars, an inlet chamber, a discharge chamber open 10 to the atmosphere and containing a thermostat, a valve opening from said inlet chamber to said discharge chamber and actuated by said thermostat, a radiator discharging into said discharge chamber, a radiator valve admitting steam from said inlet chamber to the radiator, and a thermostat located within the car actuating said radiator valve.

32. In a heating system for railway cars, the combination of a steam pipe a radiator 20 in the car having its discharge end open to the atmosphere, an inlet chamber connected with said steam pipe, valves in said chamber for admitting steam to said chamber and from said chamber to the discharge 25 end of said radiator, a thermostat located outside the car controlling said valves so as to admit low pressure steam to said inlet chamber and to admit steam to said radiator discharge to prevent freezing, inlet and discharge valves for said radiator, and an independent thermostat located in said car for operating said radiator valves responsively to the temperature conditions of the car.
